UNITED STATES PATENT OFFICE.

ERNEST B. CROCKER, OF BOSTON, MASSACHUSETTS.

DESIGN FOR A DRUM FOR ROLLER WINDOW-SCREENS.

SPECIFICATION forming part of Design No. 34,081, dated February 12, 1901.

Application filed January 5, 1901. Serial No. 42,247. Term of patent 14 years.

To all whom it may concern:

Be it known that I, ERNEST B. CROCKER, a citizen of the United States, residing at Boston, in the county of Suffolk and State of Massachusetts, have invented a new and original Design for Drums for Roller Window-Screens, of which the following is a specification, reference being had to the accompanying drawings, forming part thereof.

10 Figure 1 is an elevation of a drum for roller window-screens, showing my new design. Fig. 2 is an end view of the same. Fig. 3 is a section taken on line x , Fig. 1. Fig. 4 is a view of the end opposite to that shown in Fig. 2.

15 Similar letters of reference indicate corresponding parts.

As shown in the drawings, the leading or material feature of my design consists of the 20 circular tube A, formed with the longitudinal slot A', having parallel sides. Beyond the inner end of the slot the tube is formed up, by means of the annular shoulder B, into

the enlarged circular portion C, and beyond that, by means of the annular shoulder D, into 25 the still larger circular portion E. As shown in Fig. 3, the part B is at obtuse angles with the surfaces A and C, but the part D is at acute angles with the parts C and E, said parts being Z-shaped in cross-section. The portions E and D are formed with the recess E', the part D being cut away and the part E being severed and having its end E" folded inward and back along the part E.

Having described my invention, what I 35 claim as new, and desire to secure by Letters Patent, is—

The design for a drum for roller window-screens, as herein shown and described.

In testimony whereof I have signed my 40 name to this specification in the presence of two subscribing witnesses.

ERNEST B. CROCKER.

Witnesses:

HENRY W. WILLIAMS,
A. N. BONNEY.
